PROCESS FOR TREATING GASOLINE DISTILLATES

Bernard Sutro Greensfelder, San Francisco, and Monroe Edward Spaght, Wilmington, Calif., assignors to Shell Development Company, San Francisco, Calif., a corporation of Delaware

Application November 1, 1937, Serial No. 172,204

2 Claims. (CL 260—624)

This invention relates to a method for the treatment of hydrocarbon distillates, such as gasoline distillates, and more particularly is concerned with an improved method for neutralizing gasoline and kerosene distillates which are susceptible to improvements in their storage stabilities by the addition of small amounts of gum inhibitors, and which contain acids capable to being neutralized with alkali carbonates.

10 Our invention comprises effecting the neutralization with alkali carbonate-bicarbonate solutions obtained in the liberation of alkyl phenols from aqueous alkali metal alkyl phenolate solutions by means of carbon dioxide.

15 It is a purpose of this invention to improve storage stability of the neutralized distillates by utilizing a product which is normally wasted. Another purpose is to increase the yield of alkyl phenols recoverable from petroleum oils containing same by extraction with aqueous alkali metal hydroxide, and it is a further purpose to reduce the consumption of alkali metal hydroxide incidental to such extraction.

20 Other objects and advantages of our invention will be fully understood from the drawing representing a flow diagram of our process, in which a heated mineral oil distillate, such as a cracked gasoline distillate boiling between about 100° and 250° C. containing alkyl phenols, organic sulfur compounds and possibly hydrogen sulfide, is introduced through line 1 into fractionating unit, comprising columns 2 and 3 from a source not shown. The distillate is fractionated into two or more fractions, the flow diagram indicating 25 three fractions, namely 1st, 2nd and 3rd cut distillates. The lightest 1st cut, which may contain hydrogen sulfide, and which is preferably free from alkyl phenols, may have an end boiling point of about 150° C. It leaves the fractionating column 2 through vapor line 4, is condensed in condenser 5 and stored in storage tank 5'. The remaining fraction passes through heater or re-boiler 6 in bottom line 7 to column 3, where it is further fractionated into a 2nd cut which 30 may boil from about 150° to 205° C., containing alkyl phenols and varying amounts of hydrogen sulfide formed by thermal decomposition of organic sulfur compounds in the heater 6; and a 3rd cut preferably boiling above 205° C., also 35 containing alkyl phenols but normally being free of hydrogen sulfide.

40 The 2nd cut is condensed in condenser 8 situated in line 9, and the condensate goes to mixer 10 or to storage tank 11 from which it may be 45 introduced into mixer 16, where it is contacted

5 with aqueous carbonate-bicarbonate solution coming from the alkyl phenol plant 12 through line 13.

We have found that aqueous alkali metal carbonate-bicarbonate solutions produced in the liberation of alkyl phenols from aqueous alkali metal phenolate solutions by means of carbon dioxide, retain appreciable amounts of alkyl phenols which cannot be recovered by settling or centrifuging. These amounts normally vary between 10 about 0.5 to 5% more or less of the solution. However, by bringing the aqueous carbonate solution in contact with a naphtha or the like, a large percentage of the retained alkyl phenols can be washed out. Therefore, in mixer 10 alkyl 15 phenols retained by the carbonate-bicarbonate solution are largely returned to the raw 2nd cut distillate. Upon mixing of the two liquids the hydrogen sulfide of the distillate is absorbed by the carbonate-bicarbonate solution forming hy- 20 drosulfide, while an equivalent amount of carbonate is converted to bicarbonate.

25 The mixture of aqueous solution and distillate is transferred from mixer 10 through line 14 to settler 15, waste liquor normally containing a mixture of carbonate, bicarbonate and hydrosulfide being discarded through drain 16. The 2nd cut distillate containing the original plus recovered alkyl phenols being substantially free from hydrogen sulfide, passes through line 17 to mixer 18, where it is contacted with strong aqueous caustic alkali admitted through line 19 for the purpose of extracting the alkyl phenols from the distillate. An aqueous alkali metal hydroxide solution of about 30 to 50% concentration containing an amount of alkali metal hydroxide slightly in excess of the equivalent of the alkyl phenols in the distillate is preferred for carrying out the extraction, in accordance with the disclosure of the co-pending application of 40 Greensfelder et al., Serial No. 91,864, filed July 21, 1936, now Patent No. 2,134,390. The resulting mixture passes through line 20 to settler 21 where it is allowed to separate, 2nd cut distillate substantially free from alkyl phenols flowing 45 through line 22 to be stored, blended or otherwise utilized, or through line 23 to be acid treated. Alkali metal alkyl phenolate solution, containing some free hydroxide, is conveyed through line 23 to the alkyl phenol plant 12.

50 In the latter plant the phenolate solution is carbonated by introducing carbon dioxide, or a gas containing carbon dioxide, through line 24, normally in an amount sufficient to produce an aqueous carbonate solution containing a por- 55

tion of bicarbonate. Alkyl phenols which are thereby liberated are separated and withdrawn through line 25. The carbonate-bicarbonate solution is returned through line 13 to mixer 10 to remove hydrogen sulfide from the raw 2nd cut distillate as described before.

In order that the hydrogen sulfide be removed thoroughly from the distillate, the amount of carbonate in the aqueous solution should be somewhat in excess of the mol equivalent of hydrogen sulfide to be removed. Since, however, normally the quantities of hydrogen sulfide in the 2nd cut distillate are quite small, the available volume of carbonate-bicarbonate solution is usually more than sufficient. Moreover, the alkalinity of the carbonate-bicarbonate solution may be varied within limits by regulating the carbon dioxide input in the carbonating step, without greatly affecting the economy of the alkyl phenol recovery.

The removal of hydrogen sulfide from the 2nd cut distillate prior to extraction of alkyl phenols with aqueous caustic alkali has a considerable effect on the consumption of caustic alkali, savings varying anywhere from about 5 to 25% being commonly achieved.

The 3rd cut produced in column 3 is withdrawn through bottom line 26 to storage tank 27, and at a time when the 2nd cut runs into storage 30 11, 3rd cut distillate may be processed in the alkyl phenol recovery system, the stored 3rd cut being transferred from tank 27 through line 28 to mixer 18.

If desired, a portion or all of the carbonate-bicarbonate solution from plant 12 may be conducted through line 29 to mixer 30 where it is brought in contact with acid treated substantially sludge free 1st or 2nd cut, normally containing SO_2 , sulfuric acid esters, sulfonic acids and traces of sulfuric acid. In order to acid treat these cuts they are transferred from tanks 5' and 21 through lines 31 and 32, respectively, simultaneously or at different times, to agitator 33. Sulfuric acid is admitted to the agitator 45 through line 34, sludge is withdrawn through sludge line 35 and the desludged acid reacting distillates are moved to treater 30 to be contacted and neutralized with the carbonate-bicarbonate solution containing small amounts of alkyl phenols, introduced through line 29. During the contact the alkyl phenols are dissolved in the distillate. The resulting mixture is allowed to separate in settler 36, neutral distillate of improved gum stability being withdrawn through line 37, and waste liquor flowing out through line 38.

While in the foregoing we have shown the treatment of various distillates from a single source, it shall be understood that distillates from 60 any source which are susceptible to improvement in gum and/or color stability by means of gum inhibitors, and containing small amounts of mineral or organic acids capable of being neutralized with alkali carbonate solutions, may be neutralized to great advantage with the carbonate-bicarbonate solution produced in the liberation of alkyl phenol, in accordance with our invention.

As has been shown, our process has many advantages and is capable of considerable flexibility 70 depending upon the desired result. Thus if the primary object is economy in operation and complete recovery of the alkyl phenols contained in a hydrocarbon distillate, all of the carbonate-bicarbonate solution from the alkyl phenol plant 75 may be returned to the 2nd cut or equivalent

distillate, and the amount of carbon dioxide used for springing the alkyl phenolate solution is preferably sufficient to effect substantially complete liberation of the alkyl phenols. On the other hand if the primary purpose is to neutralize hydrogen sulfide or other acids contained in distillate oils and simultaneously to improve the gum and color stabilities of the latter, a portion or all of the carbonate-bicarbonate solution may be diverted to contact these oils, and the amount of carbon dioxide for springing may be less than that required for complete liberation of alkyl phenols, in order to raise both the alkalinity of the aqueous solution and the amount of retained alkyl phenols which will be transferred into the 15 distillates to be stabilized.

The following examples serve to illustrate the advantages of our method:

A cracked gasoline distillate boiling between 150° to 250° C. containing .2% hydrogen sulfide and .7% alkyl phenols was extracted with an amount of an aqueous 40° Bé. caustic soda solution slightly in excess over the equivalent corresponding to the acid oils plus hydrogen sulfide in the distillate. After steaming and carbonating the alkaline extract the yield of acid oils was 76% of the theoretical. When the aqueous solution produced in the carbonating step was used to effect neutralization of the hydrogen sulfide in the raw distillate prior to extraction with the caustic soda solution, the yield of acid oil was increased to 78% and the consumption of caustic soda in the extraction was reduced by about 10%.

In another test a cracked gasoline distillate boiling between 150° and 250° C. was extracted with an aqueous 40° Bé. caustic soda solution under conditions to reduce its alkyl phenol content to less than 0.07%. The treated distillate, which was doctor sour, was then treated with 8 pounds of 81% sulfuric acid per barrel of distillate, reducing its alkyl phenol content to less than 0.02%. Sludge was separated and the acid-reacting distillate was divided into two portions, one of which was neutralized with ammonia and the other with carbonate-bicarbonate solution from the alkyl phenol plant. Both neutralized portions were sweetened. Colors were equally good. However, the gum contents differed considerably, that of the distillate neutralized with carbonate-bicarbonate solution being very much lower as shown by the data below:

Neutralized with—	Series 1		Series 2	
	NH ⁴	Carbonate-bicarbonate	NH ⁴	Carbonate-bicarbonate
Normal glass dish gum...	30	17	11	9
Accelerated glass dish gum...	1,162	472	150	32
Air jet gum...	343	239	—	—
Copper dish gum...	—	—	33	21

We claim as our invention:

1. In the continuous process of neutralizing a cracked hydrocarbon distillate containing a sulfur acid and alkyl phenols, the improvement comprising treating said distillate with an excess over the equivalent to said sulfur acid of an aqueous alkali metal carbonate-bicarbonate solution containing small amounts of alkyl phenols under conditions to form two layers, an aqueous layer containing an alkali metal salt of said sulfur acid, and a distillate layer substantially free from said sulfur acid containing alkyl phenols, separating the layers and treating said dis-

tilate layer with an amount of aqueous alkali metal hydroxide of 30 to 50% concentration slightly in excess of the equivalent of said alkyl phenols to produce an extract comprising an aqueous alkali metal alkyl phenolate solution and a residual distillate, separating the extract from the distillate, carbonating the extract to liberate alkyl phenols and to produce an alkyl phenol phase and an aqueous carbonate-bicarbonate solution phase containing a portion of the liberated alkyl phenols, separating liberated alkyl phenols phase from the resulting aqueous solution phase and returning the latter to treat further amounts of said cracked distillate containing sulfur acid and alkyl phenols.

2. In the process of recovering alkyl phenols from a hydrocarbon distillate containing same and hydrogen sulfide, the improvement comprising passing said distillate through two treaters in series, treating the distillate in the second treater with a strong aqueous solution of a caus-

tic alkali in an amount sufficient to remove the largest portion of said alkyl phenols from the distillate under conditions to form two liquid layers, one comprising an aqueous solution of alkyl phenolates and caustic alkali, and the other consisting essentially of treated hydrocarbon distillate, separating the layers, adding an amount of CO₂ to the aqueous layer sufficient to convert same to a carbonate-bicarbonate solution to liberate alkyl phenols and form an alkyl phenol phase and an aqueous carbonate-bicarbonate solution phase containing a part of the liberated alkyl phenols, separating said phases, and passing the aqueous carbonate-bicarbonate solution phase through the first of said treaters in contact with said distillate, whereby the hydrogen sulfide is removed from the distillate and alkyl phenols in the aqueous solution are dissolved in the distillate.
